Inventor:

James W. Sloan.

UNITED STATES PATENT OFFICE

2,206,270

SCRAP SEPARATOR AND MATERIAL PILER

James W. Sloan, Gary, Ind.

Application July 18, 1939, Serial No. 285,198

2 Claims. (Cl. 271—86)

My invention relates to the handling of sheet metal being cut on any type of reciprocating knife shear, and has three specific objectives which are as follows:

5 First: To entirely eliminate the mixing of the scrap metal with the metal sheets, strip or blanks being cut on the shear.

10 Second: To provide a means of piling the sheared sheets, strips or blanks with the scrap metal thus separated, thereby eliminating the dangerous hand piling and separating of the cut material from the scrap material.

15 Third: By a combination of the objective set forth above, to produce a piece of equipment to efficiently function as specified, thereby greatly reducing the cost of shearing metal.

The accomplishment of these objectives will be apparent to one skilled in the art. For a better understanding of my invention, I now refer you to the drawing, in which like characters indicate like parts throughout the several views.

20 Fig. 1 is a plan view of a typical reciprocating knife shear, with the various parts and features of my invention added.

25 Fig. 2 is a section view on line 2—2 of Fig. 1.

Figs. 3, 4, 5, 6 and 7 are views of the remaining several parts of the device which will be explained in detail in the assembly and operation explanation which follows:

30 Referring to the drawing, Fig. 2, shows the material slide 3 in place with adjustable plate 1 adjusted to the entirely closed position. Fig. 1, shows a cut section of the adjustable plate 1 in the entirely closed position, variations in the size of gap can be made by moving the adjustable plate 1, on which there are two fixed pins 13 into either of the holes 14. Taking the adjustable plate, 1, away entirely will provide the maximum amount of gap 2 required for any job being 35 cut as shown (Figs. 1, 2). This variable gap provides the means of separating the scrap material from the material being cut to size.

40 Obviously, a narrow trim cut from a sheet of material will fall of its own weight into this gap 2 provided for that purpose, the material being cut to size being of a much wider dimension will overlap the gap and continue on down the slide 1.

45 A pit or receptacle may be provided to receive the scrap material which drops through this gap. Construction of the receiving rack is as follows: The rail 4 forms the base of the rack, all other

parts of the rack are related to it in one way or another as will be shown in the construction explanation following.

The pin 5 being faced with wood 15 to prevent damage to the material when it comes into contact with it, is the stop or bumper pin and slips into hole 6 and held in place by lug 5'. The pin 7 slips into hole 8 nearest to, but not less than, the width of strips to be cut, thus providing the receiving pocket for the sheared material. Two or more of these rail assemblies formed by means of pins 5 and 7 and rail 4 will be needed to form the rack according to the length of material being cut, and can be spaced and keyed into position by means of pins 10 which slip into holes 11 as selected. Pins 10 having been slipped into the selected holes 11 being of sufficient length will protrude above the level of the floor, thus providing the keys to hold the rail assemblies in the locations selected, by means of holes 9 in the bottom of rail (Fig. 4) which will accommodate the protruding pin or key as shown Fig. 2.

20 Fig. 5 shows a view of pin 7 having three spacers 12 telescoped over it which will be found very effective in procuring the desired spacing between pin 5 and pin 7 when necessary.

Having thus described the objectives and the construction of my invention, I claim as new and useful and desire to protect by Letters Patent the following:

30 1. A stacking device for a shear comprising, rail means, provided with a hole having a key-way, buffer pin means having key means removably secured to said rail means, the said rail means, further provided with a multiplicity of 35 holes, and spacer pin means removably secured to said stacking device by virtue of said holes, the said stacking device adapted to receive and stack sheared material thru gravitational action.

40 2. A stacking device for a shear comprising, rail means provided with a hole having a key-way, buffer pin means provided with key means removably secured to said rail means, the said rail means further provided with a multiplicity of 45 holes, spacer pin means removably secured to said rail means by virtue of said holes, and sleeve means telescopically and removably secured to said spacer pin means, the said stacking device adapted to receive and stack sheared material thru gravitational action.
